(57) **CLAIM**

The ornamental design for a cookware utensil with selectively interlocked component parts, as shown and described.

DESCRIPTION

FIG. 1 is a top, front and left-side pictorial view of a cookware utensil with selectively interlocked component parts showing my new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof;

FIG. 6 is a bottom plan view thereof;

FIG. 7 is a top plan view thereof, showing the component parts in an unlocked position; and,

FIG. 8 is a top, front and left-side pictorial view thereof, showing the component parts unlocked and separated to illustrate interior contours.
